PORTABLE PHONOGRAPH

Tobin Wolf, 447 Essex Ave., Bloomfield, N.J.

Filed Aug. 13, 1964, Ser. No. 81,270

Term of patent 14 years

(Cl. D56—4)

The figure is a perspective view of a portable phonograph, with the case open, showing my new design.

The dominant features of my design reside in the portions shown in full lines.

I claim:

The ornamental design for a portable phonograph, substantially as shown and described.
